UNITED STATES PATENT OFFICE

NORMAN P. HARSHBERGER, OF SCARSDALE, NEW YORK, ASSIGNOR TO BAKELITE
BUILDING PRODUCTS CO. INC., OF NEW YORK, N. Y., A CORPORATION OF DELAWARE

DESIGN FOR ROOFING

Application filed September 17, 1932. Serial No. 44,988. Term of patent 14 years.

To all whom it may concern:

Be it known that I, NORMAN P. HARSHBERGER, a citizen of the United States, residing at Scarsdale, in the county of Westchester and State of New York, have invented a new, original, and ornamental Design for Roofing, of which the following is a specification, reference being had to the accompanying drawing, forming part thereof.

In the drawing, showing my new design, Figure 1 is a detail view of the roofing element shown in Figure 2, and Figure 2 is a plan view of the roofing showing my new design, parts being broken away.

I claim:

The ornamental design for roofing, as shown.

NORMAN P. HARSHBERGER.
